D8-321.

OR D5,964

EX

EXAMINER'S ROOM.

[DESIGN.]

A. E. YOUNG.

Glass-Heads for Door-Knobs.

No. 5,964.

Patented June 25, 1872.

A

B

Inventor

A. E. Young

Witnesses

C. L. King

C. H. Abbott

5,964

UNITED STATES PATENT OFFICE.

ALONZO E. YOUNG, OF BOSTON, MASSACHUSETTS, ASSIGNOR TO FRANCIS L. KING, OF SAME PLACE.

DESIGN FOR GLASS HEAD FOR DOOR-KNOBS.

Specification forming part of Design No. 5,964, dated June 25, 1872.

Specification describing a Design for a Glass Head for Door-Knobs, Bell-Pulls, &c., invented by ALONZO E. YOUNG, of the city of Boston, county of Suffolk and State of Massachusetts.

The nature of my design consists in an improved form for that part of door-knobs, bell-pulls, &c., which may be properly designated as the head, and is fully represented in the accompanying photographic illustration and the model, to which reference is herein made.

A represents a perspective view of the side of my improved design for a head or knob for door-knobs, bell-pulls, &c., showing the grooved projection D. B represents a perspective view of the face of a similar head.

The front face of the head is perfectly plain. The back is also plain, with the exception of the projection D. The front and back are parallel with each other, the thickness between being about three-fourths of an inch. The extreme limits of the sides are in the octagonal form, as will be seen in Fig. B; but the corners are truncated both front and rear, which leaves the front and rear face still in the octagonal form, but of less size, and the angles all changed. The projection D in the central part of the back of the head is about one-fourth of an inch long; the sides are circular, with the groove E extending around the periphery. The diameter is about one inch. The end of the projection may be ornamented, as shown, but said projection forms no part of this design application.

What I claim as my invention, is—

A design for a head or knob for door-knobs, bell-pulls, &c., made substantially in the form above described.

Boston, Massachusetts, April 25, 1872.

ALONZO E. YOUNG.

Witnesses:

F. L. KING,
C. H. ABBOTT.